UNITED STATES PATENT OFFICE.

PATRICK W. PENTA, OF MEDFORD, MASSACHUSETTS, ASSIGNOR TO WILSON MANUFACTURING COMPANY, OF BOSTON, MASSACHUSETTS, A CORPORATION OF MASSACHUSETTS.

KEY CASE.

Application filed January 12, 1927. Serial No. 160,624.

This invention relates to key cases and particularly to such cases having display pockets for documents or papers of various kinds, and it aims to provide an improved case having a novel key plate carrying panel, and, among others, the advantages and novel features hereinafter mentioned.

In the drawings of one embodiment selected for illustration and description,

10 Fig. 1 is a plan of the case closed;

Fig. 2, a plan of the case opened with the key carrying side of the key panel uppermost, showing a paper held unfolded in the pocket;

15 Fig. 3, a similar view with the opposite side of the key carrying panel uppermost, showing a folded paper or small card in the pocket;

Fig. 4, a detail on an enlarged scale of the 20 method of securing the key hooks to the key plate; and

Fig. 5, a horizontal section on the line 5—5 of Fig. 2.

Referring to Figs. 1 to 3, my novel key 25 case comprises a flexible back member 1 of any suitable material, as leather, divided by folds 2, 3, into three sections 4, 5, 6, and preferably provided near its opposite ends with suitable snap or other fastener members 7, 8.

The center section 5 may be provided with a pocket or paper receptacle 9 by securing to that section at the top and bottom thereof the pocket forming members; as a strap 35 10 which may be cut away somewhat at its central portion to resemble a frame and to provide the window 11, by means of which any card or other document 12 thereunder may be easily read. By securing the member 10 to the section 5 at its top and bottom edge only, an entrance may be had from either side of the strap to the pocket 9. This feature not only permits the use of the pocket for a card, folded bills or the like, 40 but also permits its use for bills or papers 122 to be inserted therein in flat or unfolded condition, Fig. 2, and thus more readily readable. The strap 10 also has hinged to it along its, Fig. 2, left hand edge a key carrying panel 13 of leather or other suitable material, to the upper end of which on one face, Fig. 2, are secured the key plate 14 and hooks 15 mounted thereon by eyes 45 155, having a swivel connection with the

plate, and thus permitting more free and 55 convenient use of the keys.

The pocket forming member 10 acts to stiffen the panel 5 and thus prevent it from being crushed or curled up in the pocket under the action of the pressure from the 60 pocket and its contents. The panel 13 may also be provided on one face with a flap 16 stitched thereto by the lines of stitching 17, 18, having an opening or window 19 for displaying a calendar or any article or document and providing also a pocket 20 for receiving cards or the like. The member 10 has a fastener member 21 adapted to cooperate with a member 22 on the key panel 13.

The foregoing construction has the advantages of providing a concealed mounting of the plate 14, the eyelet fasteners 23 therefore not showing on the back of the case itself as is usual; a fastening for the frame 10 and pocket 20; and a swinging and therefore 75 more adaptable panel 13 for the key plate 14, permitting more ready and convenient use of the several key hooks and keys thereon, than can be had where the key plate is secured to the back of the case in the usual 80 manner. Further, the keys do not come into contact with the paper 12 in the pocket 9 to mar or even destroy it, as the keys are on the opposite side of the panel 13.

This invention is not limited to the particular embodiment thereof described and illustrated, and I claim:

1. A key case comprising a back member with a plurality of sections, one of which carries a pocket forming member with a 90 window therein for carrying and displaying papers, a key carrying panel with a key plate hinged to the pocket forming member to provide a swinging attachment of the key carrying member to the back member. 95

2. A key case comprising a back member with a plurality of sections, one of which carries a pocket forming member with a window therein for carrying and displaying papers, a key carrying panel with a key plate hinged to the pocket forming member to provide a swinging attachment of the key carrying member to the back member, a pocket on the key carrying panel and means to fasten said panel and pocket to the display pocket member and an entrance to the latter pocket from each side thereof for carrying documents in non-folded position. 100 105

3. A key case comprising a back member with a plurality of sections, one of which carries a double opening pocket forming member with a window therein for carrying and displaying papers while held across the central portion, a key carrying panel with a key plate having swivel eyes with key hooks hinged to the pocket member to provide a swinging attachment of the key carrying member to the back member, a pocket on the key carrying panel with a window therein and means to fasten said panel and pocket to the display pocket member and an entrance to the latter pocket from each side thereof for carrying documents in non-folded position.
4. A key case comprising a flexible back member 1 with a plurality of sections 4, 5, 6, sections 5 provided with the strap 10 secured thereto at the top and bottom edges leaving both side edges unsecured for the insertion of unfolded papers therein so that
- the reading matter thereon may be legible, said member 10 having a window 11 therein to permit display of the printed matter 25 upon the paper adjacent the section 5, a key-carrying panel 13 with key-retaining members thereon and hinged to the pocket member 10 to provide a swinging attachment for the key-carrying member relative to the back 30 member, a pocket forming member 16 attached to the panel 13 and having a window 19 therein for reception of and display of cards or the like, means 21 and 22 on the panels 13 and 5 respectively for locking 35 them together, whereby papers beneath the pocket forming member 10 may be readily inserted and withdrawn beneath the panel 13 without unfastening the same from the panel 5. 40

In testimony whereof, I have signed my name to this specification.

PATRICK W. PENTA.
